(57) **CLAIM**

The ornamental design for a white noise sound machine, as shown and described.

DESCRIPTION

FIG. 1 is a perspective view of a white noise sound machine showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the white noise sound machine that form no part of the claimed design.
